United States Patent Office

Des. 178,620
Patented Aug. 28, 1956

178,620

COMBINED SPECTACLES AND HEARING AID

Raleigh E. Tresise, Chagrin Falls, and Paul D. Kendall,
Gates Mills, Ohio

Application January 20, 1956, Serial No. 39,857

Term of patent 14 years

(Cl. D57—1)

Fig. 1

Fig. 1 is a perspective view of a combined spectacles and hearing aid embodying our new design;

Fig. 2 is a side elevational view thereof taken on lines 2—2 of Fig. 4;

Fig. 3 is a side elevational view thereof taken on lines 3—3 of Fig. 4; and

Fig. 4 is a bottom plan view thereof.

The dominant features of our design reside in the portions thereof indicated by solid lines.

We claim:

The ornamental design for a combined spectacles and hearing aid as shown and described.
